W.J. FitzGerald & Co.

UNITED STATES PATENT OFFICE.

FRED E. BURNETTE, OF NORTHBORO, IOWA.

CRANK-CASE-REINFORCING MEANS.

1,326,844.

Specification of Letters Patent. Patented Dec. 30, 1919.

Application filed March 24, 1917. Serial No. 157,161.

To all whom it may concern:

Be it known that I, FRED E. BURNETTE, a citizen of the United States, residing at Northboro, in the county of Page and State of Iowa, have invented certain new and useful improvements in Crank-Case-Reinforcing Means; and I do hereby declare the following to be a full, clear, and exact description of the invention, such as will enable others skilled in the art to which it appertains to make and use the same.

This invention relates to a crank case reinforcing means, and has for one of its objects to provide a device which can be readily attached to and supported by the frame of a motor propelled vehicle for reinforcing the crank case of the engine, or which may be also applied to a crank case which has become broken or damaged for reinforcing and supporting the same.

Another object is to provide the device with means whereby the same may be adjusted to attach the same to frames and crank cases of different sizes and to further provide the device with means for embracing the drain tube of the crank case to prevent displacement of the device when applied to a crank case.

These and other objects and advantages will more fully appear as the nature of the invention is more clearly understood from the construction, combination and arrangement of the parts thereof as fully set forth in the following specification, defined in the subject matter of the claims, and illustrated in the several views in the accompanying drawings, in which,

Figure 1 is a vertical transverse sectional view through the frame of the vehicle and the crank case of the engine showing the invention in applied operative position thereon.

Fig. 2 is an edge view of the invention.

Fig. 3 is a bottom plan view thereof with the supporting bars broken away.

Referring to the drawings, wherein similar reference characters denote corresponding parts throughout the several views, 1 denotes the frame or chassis of a motor driven vehicle upon which are secured by the bolts 2 the apertured ears 3 of the lugs 4 upon the outer sides of the crank case 5, the crank case 5 being provided with the semi-circular bearings 6 for the engine shaft

and the drain tube 8 provided with the plug 9.

Applied to the under side of the crank case 5 is the reinforcing plate 10 provided with the central opening 11 surrounded by the annular reinforcing flange 12 for surrounding and engaging the drain tube 8. Upon one side of the plate 10 in proximity to its ends are the apertured reinforced ears 13, through which apertured ears project the threaded ends 14 of the attaching and supporting straps or bands 15, and upon the threaded ends 14 of the bands 15 at the inner sides of the ears 13 are the nuts 16 adapted to bear against the inner faces of the ears 13 when screwed home upon the threaded ends 14 of the straps or bands 15 for adjustably maintaining the plate 10 firmly positioned upon the under side of the crank case 5. The attaching and supporting bands 15 extend obliquely upwardly and outwardly from the ears 13 and are provided with the apertured vertical members 17 and the inturned apertured members 18, the apertured members 17 engaging the outer faces of the frame 1 and being secured thereto through the medium of the bolts 19 which project through the apertured members 17, the filler plugs 20 within channel bars of the frame 1 and the extensions of the lugs 4 of the crank case 5, the apertured members 18 engaging the upper surfaces of the bars of the frame 1 and being retained thereon through the medium of the bolts 2, the members 18 being seated within the recesses 21 formed in the under sides of the ears 3 of the lugs 4 of the crank case 5.

In constructing my device I preferably form the plate 10 of suitable steel, preferably mild steel, and of a sufficient width to enable the opening 11 to be formed therein for embracing the drain tube 8 and without weakening the plate 10 at this point, and I also preferably form the reinforced ears 13 of malleable iron, the attaching and supporting bands 15 being preferably formed of the same material as the plate 10.

From the foregoing it will be seen that I produce a device for efficiently reinforcing the crank case of an engine, and one which is not only readily applied upon a motor propelled vehicle, but which can also be adjusted to accommodate the same to frames and crank cases of varying sizes. Further-

more, by applying my invention to a crank case, the crank case is efficiently reinforced at a point where the same is most likely to become broken, or should a crank case be 5 broken or cracked the same will be efficiently reinforced by the application of my invention thereto, and by the provision of the opening in the plate 10 for surrounding and engaging the drain tube 8 of the crank case, 10 it is practically impossible for the device to become displaced thereon by either lateral or longitudinal movement.

While I have herein shown and described the preferred embodiment of the invention 15 I may resort to variations and modifications therein from time to time to meet the exigencies of the case without departing from the spirit of the invention or the scope of the claims.

20 Having described my invention, what I claim as new and desire to secure by Letters Patent, is:—

1. In a device of the character specified, the combination with the frame of a vehicle, 25 and the crank case thereof, of supporting bands suspended upon said frame, a plate for engaging and supporting said crank case, and means upon the ends of said plate for adjustably engaging the lower ends of 30 said supporting bands.

2. In a device of the character specified, the combination with the frame of a motor propelled vehicle, and the crank case of the engine thereon, provided with a drain tube, 35 of supporting bands secured upon said frame and extending downwardly and inwardly therefrom and provided with threaded ends, a plate for snugly engaging the under surface of said crank case and provided with a 40 reinforced opening for surrounding and snugly engaging said drain tube, reinforced apertured ears upon the ends of said plate for receiving the threaded ends of said supporting bands, and nuts upon said threaded

ends at the inner sides of said ears for adjustably maintaining said plate upon said supporting bands.

3. A support for transmission casings embodying a plurality of elements, certain of which elements have their outer terminals 50 secured to the beams of an automobile chassis, and a certain other element which extends under and supports the said casing between said beams.

4. A support for transmission casings embodying a plurality of elements, certain of which elements have their outer terminals 55 secured to the beams of an automobile chassis, and a certain other element which extends under and supports the said casing 60 between said beams, and means for adjustably connecting said elements.

5. A support for transmission casings embodying a plurality of elements, certain of which elements have their outer terminals 65 secured to the beams of an automobile chassis, and a certain other element which extends under and supports the said casing between said beams, the last-mentioned element being constructed to span or bridge 70 the drain cock depending from said casing, and means for adjustably connecting said elements.

6. A support for transmission casings comprising an element which extends under 75 and supports the said casing and spans the drain cock depending therefrom, and bolts adjustably connected with said element and having means at their outer ends for securing the same to the beams of an automobile 80 chassis.

In testimony whereof I have signed my name to this specification in the presence of two subscribing witnesses.

FRED E. BURNETTE.
